UNITED STATES PATENT OFFICE.

ERNEST THÉODORE GODDEFROY, OF BRUSSELS, BELGIUM.

WAX SEAL AND APPARATUS THEREFOR.

Application filed October 22, 1923, Serial No. 670,199, and in Belgium August 23, 1923.

It has been found that when robbing envelopes or parcels sent by mail or otherwise, the robbers operate generally by quickly taking a specimen or type of the seals, and after having opened the wrapper or envelope and stealing the contents, re-affix counterfeit seals obtained by means of the type previously formed, without possibility of perceiving fraud even by a careful inspection.

The present invention consists in a seal, as well as in an arrangement of apparatus suitable for its execution, impossible to reproduce by casting, without leaving traces such that the fraud will immediately become apparent. The features of the seal, the different steps in its execution, as well as the main characteristics of a preferred way of constituting the apparatus used for producing it, will be clearly exposed in the following complementary description with reference to the accompanying drawings, in which:

Fig. 1 is a front elevation of an apparatus suitable for producing the seal of the invention.

Fig. 1^a is a longitudinal section of a modified form of construction.

Fig. 2 is a longitudinal section of the apparatus of Fig. 1, taken at right angle to that of Fig. 1.

Fig. 3 is a plan view of the underside of the apparatus.

Figs. 4, 5, 6, 7, 2^a, 3^a and 4^a are details. As represented, the apparatus comprises essentially a cylindrical body 1 of copper, steel or any other suitable material in which engages a rod or plunger 2, held and guided by the central opening of a removable cap 3. At the lower part of the rod or plunger 2 is mounted a member 4 suitably attached to the plunger 2 and sliding within the body 1.

The rod or plunger 2 is normally held raised by a spring 5 inserted in a hollow 6 provided in the cap 3 and between the cap and an operating member 6^a mounted on the plunger.

The lower part of the member 4—member shown cylindrical in the present case—may be of any desired shape, round, square, oval, star shaped, etc., and is circular in the example considered. A die or stamp 9 constituted by a letter, figure or design—a square die in the example considered—is fixed or otherwise formed at the underside

of the member 4. This die or stamp is preferably beveled and mounted so as to project slightly from its supporting base.

In an alternative form of carrying out the invention (Figure 1^a), the interior part of the body 1 is preferably of cylindrical form, and a die similar to member 4 of the preceding construction is mounted on the base of the plunger 2, the said die being made with a section of the desired shape and preferably with its lower end cut slightly concave.

When the plunger 2 is pressed down, the base of the member 4 or of the die 4^a cooperates with the upper edge of a central opening, of identical section, cut in the wall 8 which forms the lower side of a chamber 7 formed at the base of the body 1, in order to cut out a part of a strip of paper 11^a passing under the stamps or dies, as hereafter explained. This strip 11^a unwinds from a spool 12, crosses the chamber 7 by passing through the lateral slots 11 in the body 1, and winds onto a spool 13. The two spools 12 and 13 are mounted on lateral supports 14 attached to the body 1, and the shafts, which are fixed to the spools so as to turn with them, are formed with extensions of eyelet shape (Figure 5) or any other suitable operating member.

In the alternative arrangement shown in Figure 1^a the base of the body 1 is joined and attached to the said body, for example, by screw threads, and the central opening forming the punch matrix evidently has a section of a shape identical with that of the punch 4^a. Under the base 8 a seal 10 is mounted in any suitable manner. In addition to the special inscriptions, this seal 10 has a central opening corresponding to that of the base 8. In the alternative construction shown in Figure 1^a, the central opening 10^a in the seal 10 is slightly larger than the opening in the base or matrix 8 and follows or surrounds the outline of the said opening.

The plunger brings the punches back into the chamber 7 under the action of the spring 5, but when the plunger is completely pressed down, the punch 4 penetrates into the opening in the matrix 8 cutting out a piece from the strip 11^a, a fresh part of which has previously been brought over the opening of the matrix 8 by suitably rotating the spool 13, and the piece cut out is carried down by the punches or dies so

that when the seal is applied to a mass of hot wax spread on a support, the piece of paper is inlaid in the wax forming the central part of the said seal.

5 According to the invention, the strip 11 will preferably be made of paper on which is printed the individual monogram of the people using the seal. Preferably also the strip will have special perforations, the 10 relative arrangement of which will moreover be reproduced by slight projections on the under surface of the punch or punches, so that when the seal is formed, the piece cut from the paper strip being pressed into 15 the hot wax, the latter will enter the perforations and spread out over them, thus increasing considerably the adherence.

In order to strengthen the sealing of the paper, four small grooves 15 are cut on the 20 under side of the part 10 of the seal, which facilitate the flow of hot wax towards the center, and on the other hand, as in Figures 1^a and 2^a corresponding grooves are cut on the interior vertical sides of the matrix, 25 causing the wax to overflow on the punched out paper or as in the alternative shown in Figures 3^a and 4^a, and as previously indicated, the opening of the seal 10 is made slightly larger than that of the matrix, 30 so as to obtain a continuous rim of wax overflowing all around the paper.

According to another feature of the invention, a diametrical groove 16 is provided at the underside of the part 10 of the seal, 35 which groove has two small cavities or stars 17 cut in near its ends. Before affixing a seal, a small long-fibered string 18 is drawn into the said groove. The string 18 is impregnated with aniline, or any other similar dye, during a previous treatment, and unwinds from a spool 19 mounted laterally on the body 1. The free end of the string is attached to a spring stop 20 mounted on the opposite side of the body 1. When the 40 seal is affixed, the string is caught in the wax which penetrates into the cavities 17 and into the central opening of the part 10 of the seal, so that the said string is thus solidly attached at three points, while passing 45 above the wax of the seal between the points of attachment.

In order to affix a seal, and after having first brought a fresh section of the strip 11 under the punches or dies, then introduced 50 the string 18 into the groove 16, attaching its free end to the stop 20, and finally caused a suitable quantity of wax to flow onto the envelope or other support, the seal is stamped by pressing the crown 10 of the seal into the 55 wax and then thrusting down the plunger 2 into the body 1.

The soft wax penetrates into the cavities, 60 slots, grooves, clearances, partially covering the string as previously indicated. At the 65 same time the piece of the strip 11 cut out

by the punches inlays on the central part of the seal.

Thus a wax (or similar material) seal is provided said seal having essentially: a base attached to the wrapper or support, crossed 70 diametrically by at least one long-fibered string previously impregnated with aniline or other similar dye, and attached at least three points in the wax base, but remaining entirely uncovered between the points of attachment, the central raised portion being 75 covered by a paper wafer inlaid in the wax forming the said raised portion.

In case it is attempted to cast the seal, the string fibers will penetrate the mass of 80 plaster and it will become practically impossible to detach the cast. Moreover, the aniline with which the string is impregnated will rapidly loose its color in contact with the water used for tempering the plaster, 85 and will stain the parts of the envelope or support around the seal.

Even though it were possible to obtain the 90 usable cast, it would nevertheless be absolutely necessary to cut out the cast along the string in order to free the string of the original seal, and to have a second string identical in every way with that used in making the genuine seal.

In addition, it is doubtful whether the 95 paper wafer, inlaid in the central part of the seal, could be separated in a condition enabling it to be used again without the fraud being immediately apparent, particularly when the paper is impregnated by 100 the moisture from the plaster.

Further on account of the length of time and the difficulty of the work of reproduction, it is improbable that thieves would 105 attempt to execute it.

Finally, in order that it might be impossible to detach the seal entirely by means of a hot blade, it will preferably be affixed according to the special method described in the application No. 670,198 in the name of 110 the same inventor, and of the same date as the present.

It is to be understood that the invention is not limited to the particular examples of seal and apparatus described and illustrated, but that it includes all the alternative ways of carrying out the invention.

Having now described my invention, I declare that what I claim is:

1. An apparatus for producing a seal of 120 wax or similar material comprising a base, a hollow body on the base, a matrix for the seal fixed on the base and within the body, a matrix for the central part of the seal, a member carrying the last mentioned matrix and slidably in the body, and an elastic member between the hollow body and the slidably member for disengaging the central matrix from the first mentioned matrix of 125 the seal.

2. An apparatus for producing a seal of wax or similar material comprising a hollow body, a plunger slidable therein, a resilient member between the body and plunger, 5 a ring-like matrix fixed to the underside of the hollow body, a central matrix fixed to the plunger and including a die for cutting and a die for stamping, and the base of the hollow body including a cutting matrix co- 10 operating with the cutting die of the central matrix.

3. An apparatus for producing a seal of wax or similar material comprising a hollow body, a plunger slidable therein, a peripheral matrix fixed to the hollow body, a central matrix fixed to the sliding plunger, 15 said central matrix comprising a punching die the base of the hollow body including a cutting matrix, and means for disengaging 20 said central matrix from said peripheral matrix, substantially as and for the purposes set forth.

4. An apparatus as claimed in claim 3, 25 wherein the hollow body is provided with slots adapted to guide a band inside of the body and under the central matrix, and

means mounted laterally on the hollow body and adapted for supporting and moving the band.

5. An apparatus as claimed in claim 1, 30 wherein the operating side of the first mentioned matrix is provided with a slot and also provided with cavities near the ends of the slot, substantially as and for the purposes set forth. 35

6. Apparatus as claimed in claim 1, wherein the string holding spool is mounted on the hollow body, and string securing means mounted on the opposite sides of the body, substantially as and for the purposes 40 set forth.

7. An apparatus according to claim 1, wherein the first mentioned matrix is of a ring-like shape and is provided with a plurality of radial grooves and slots on the 45 operating side and also provided on the vertical side with corresponding grooves to facilitate the feeding of the wax from the central part of the seal.

In testimony whereof I affix my signature. 50

ERNEST THÉODORE GODDEFROY.
